UNITED STATES PATENT OFFICE.

RICHARD J. VAUGHAN, OF LARAMIE, WYOMING.

RAILWAY-DERRICK.

1,182,232.

Specification of Letters Patent.

Patented May 9, 1916.

Application filed May 28, 1915. Serial No. 31,000.

To all whom it may concern:

Be it known that I, RICHARD J. VAUGHAN, a citizen of the United States, and a resident of Laramie, county of Albany, State 5 of Wyoming, have invented certain new and useful Improvements in Railway-Derricks; and I do declare the following to be a full, clear, and exact description of my invention, such as will enable others skilled in 10 the art to which it appertains to make and use the same, reference being had to the accompanying drawings, forming a part hereof.

This invention relates to traversing hoists, 15 and more especially to portable rotary derricks; and the invention consists broadly in the construction of a machine mounted on a platform car and carrying a derrick for removing old rails and laying new ones and 20 for like service as in wrecking.

Specifically the invention consists in the use of a fixed mast of only such height that it will pass through tunnels and beneath 25 bridges, a boom of good length with means for raising it to the desired height and for sluing it, and special means for pivotally supporting it in the coupling at one end of the platform car so that it may be 30 detached from said coupling and run back onto the platform while the car is moving from point to point.

With these and other objects in view, which will become apparent in the following detail description, with reference to the 35 accompanying drawings, the invention will be described in detail.

In these drawings, Figure 1 is a side elevation view of the track laying machine; Fig. 2 is a plan view of the same; Fig. 3 40 is a front end view, with the boom removed, showing the manner of bracing the mast; Fig. 4 is a detail view showing the block and sheaves for retaining the hoisting cable against displacement during the lateral 45 movement of the boom; Fig. 5 is an edge view of the block and sheaves shown in Fig. 4; Fig. 6 is a detail view of the rail tongs, the full lines showing the same in the disengaged position, while the dotted 50 lines show the same in the engaged position; Fig. 7 is a detail view of the clutches for controlling the travel of the machine forward and rearward; Fig. 8 shows the joints by which the boom is permitted to 55 swing either vertically or laterally; Fig. 9

is a side elevation view showing said joints; and Fig. 10 is a detail view showing the sheave mounted thereon near the lower extremity of said mast.

Corresponding and like parts are referred to in the following description and indicated in all the views of the accompanying drawings by the same reference characters.

Let the numeral 1 represent the forward pair of wheels of the usual form employed on railway cars and trucks, the same having flanges to prevent the wheels from disengaging the track, and 2 represents a similar pair of rear wheels.

3 is the front axle and 4 is the rear axle, 70 the wheels 1 and 2 being keyed to said axles to revolve with the latter, the axles 3 and 4 being journaled in suitable journal boxes 5 formed on the frame 6. A platform 7 is mounted on the frame 6, the said platform 75 7 supporting a motor 8, windlass 9, mast 10 and the boom 11.

The outer extremity of the engine shaft 12 is provided with two pulleys 13 and 14, which are made fast to said engine shaft 80 and over which, plain belt 15 and crossed belt 16 respectively pass, the said belts also respectively passing around pulleys 17 and 18 mounted on the axle 4 to revolve independently of said axle, except when engaged 85 with the latter, as will be hereinafter explained. These pulleys 17 and 18 are held against longitudinal movement on the axle 4 by means of fixed collars 19, 20 and 21. These pulleys 17 and 18 are each provided 90 with a complementary clutch, the said clutches being respectively designated 22 and 23. Clutch members 24 and 25 are splined to the axle 4, the said clutch members being provided with circumferential 95 grooves 27 and 28 in which are received the arms 29 and 30 of the clutch shifter 31, the said clutch shifter forming a yoke with the arms thereof.

A lever 32 is pivoted to the clutch shifter 100 31, and is also pivoted intermediate its extremities to the platform 7, on the under side of the latter, as shown at 33. The forward part of the lever 32 is bent at an angle and extended upwardly through a slot 34 formed 105 in the platform 7, and the forward extremity of said lever is approximately horizontally disposed above the platform in a convenient position for operation by the operator of the machine. The clutch members 24 and 25 are 110

controlled by the clutch shifter 31, and by operation of this clutch shifter, by the lever 32, either of the clutch members 24 or 25 may be caused to engage with the complementary clutch 22 or 23, as the case may be. The clutch members 24 and 25 are keyed to the axle 4 by means of keys 35', whereby the said clutch members turn with the axle 4, the said clutch members being permitted to move longitudinally on said axle by means of the spline heretofore described. By starting the engine 8 power may be transmitted to the rear axle 4 of the truck to propel the same either forwardly or rearwardly as may be desired. By manipulation of the lever 32 in the proper direction, the clutch member 25 will engage the complementary clutch 23 of the pulley 17, whereby the pulley 17 is acted upon by the belt 15, whose opposite sides travel parallel, propelling the truck forwardly, power being transmitted to the axle 4 through the medium of the elements heretofore described. Now, in order to reverse the direction of travel of the truck, the lever 32 will be shifted in the opposite direction, causing the clutch member 24 to move into engagement with the complementary clutch 22 thereby engaging the pulley 18 to revolve with the axle 4, and the same operation of the lever 32 will simultaneously disengage the clutch member 25 from the complementary clutch 23, allowing the pulley 17 to revolve independently of the axle 4, and through the medium of the crossed belt 16, power will be transmitted from the engine 8 to the axle 4 to propel the truck rearwardly.

The engine 8 and the windlass 9 are mounted on the rear end of the platform 7, directly above the rear axle 4. The windlass 9 is provided with a drum, or spool 35, the windlass adapted to be operated by power transmitted from the engine 8 through the medium of a counter shaft 36 journaled parallel with the axis of the windlass 9. A gear 37 is fixedly secured to the shaft of the drum, or spool 35, which meshes with a gear 38 made fast to the counter shaft 36. A gear 39 is also made fast to the opposite extremity of the counter shaft 36 and meshes with a gear 40 mounted on the engine shaft 12. The drum 35 is controlled by a clutch 42, which, though not shown in detail in the drawing, is operable to either permit the drum 35 to remain idle while the engine is in operation, or to operatively connect said drum with the engine, whereby the latter will actuate the drum.

The mast 10 is mounted upon the forward end of the platform 7 in a vertical position, the same being stationarily held by means of braces 43 and 44 and guys 45 and 46 passing around metal thimbles 48 in eyelets 47, and secured to the platform 7, on the under side of the latter, as shown at 45' and 46'.

An eyelet 50 is secured to the front side of the mast 10 near the upper extremity of the latter, and through which eyelet a supporting cable 51 is passed, its extremity being secured by means of a clamp 78 whereby the length of the cable 51 may be regulated for controlling the inclination of the boom 11. The other extremity of the cable 51 is secured to a clevis 66, which is pivoted to the outer extremity of the boom 11. 75

An aperture is formed in the lower portion of the mast 10 but above the platform, and in which a sheave 53 is journaled, as shown at 54, the aperture being designated 52. A hoisting cable 41 passes under this sheave 53, 80 one extremity of said hoisting cable being connected with the drum 35, while lifting tongs 68 are secured to the other end of said cable. A sheave 64 is journaled in an aperture formed near the outer end of the boom 11, as shown at 65, and over which sheave, the cable 41 passes.

A block 55 is secured to the lower portion of the mast 10, and in which block, a pair of sheaves 56 are journaled, as shown at 57, 90 said sheaves being disposed forward of the sheave 53 to engage the hoisting cable 41 during the lateral movement of the boom 11 to prevent disengagement of the hoisting cable 41 from the sheave 53 and reduce to a 95 minimum the wearing of the cable 41 incident to friction.

A forked coupling member 58 is mounted on the forward end of the truck of the platform car and receives the removable coupling member or block 59, the latter being pivoted in the fork 58 by means of a vertical coupling pin 60. The lower extremity of the boom 11 is pivoted in the block 59 by means of a horizontal bolt or pin 61, passing 105 through the metal plates 62 and block 59, said plates being disposed on opposite sides of the boom 11 and forming a bifurcation for the reception of said block 59. By virtue of this construction, the outer end of the 110 boom 11 may be adjusted vertically and moved laterally in either direction to describe an arc of a circle.

A ring 67 is secured to the forward extremity of the hoisting cable 41, and in 115 which are hung the rail-lifting tongs 68, which, after having engaged the rail as represented by dotted lines, are held in their engaging position by means of a fastening device 69 in the shape of a loop engaging 120 the tongs.

A band 70 is mounted on the boom 11, the same being provided with eyelets 71 on opposite sides of the boom, to which the extremities of chains 72 and 73 are secured, 125 the other, or rear extremities of the said chains being passed through eye-bolts 74 and 75, rising from the floor of the platform car near its corners, the chains being provided with hooks 76 and 77 adapted to 130

engage in links of the chains 72 and 73 to sustain the boom 11 in any desired position of lateral adjustment.

In the use of this machine, the hoisting cable 41 is led from the windlass under the sheave 53 and through the mast, thence between the sheaves 56 and along over the boom, and thence over the sheave 64 and downward to the tongs; and by driving the windlass in one direction or the other the tongs may be utilized to raise or lower a rail or a piece of wreckage. In ordinary track laying and with a boom whose outer end is relatively as high as shown in Fig. 1, the length of the hoisting cable 41 beneath the sheave 64 is such that it may not be necessary to slue the boom in order to put a rail in place; but to displace a worn rail and lay it on the siding or to move a piece of wreckage onto the siding or something from the latter onto the road bed, it will doubtless be necessary to turn the boom on its main pivot which is the coupling pin 60. In that case the hooks 76 and 77 are disengaged from the links in their own chains, and the latter used as slue lines. In fact, if this derrick is to be employed for work alongside the road bed, the chains may be adjusted to hold the boom in a position oblique to the length of the road. Attention is directed, however, to the length of the boom 11 relative to the height of the mast 10, as seen in Fig. 1, and it may be assumed that as therein shown the outer end of the boom is so high that it would not pass through ordinary tunnels and under railroad bridges. Therefore after using this machine it will be necessary to lower the boom in order to take the platform car back to the shops. This is accomplished by letting out the slue lines or chains, loosening the clamp 78 and letting out the supporting cable 51, and then revolving the windlass to loosen the hoisting cable 41; after which the outer end of the boom comes down to within reach of the workmen, the coupling pin 60 is raised to disengage the members 58 and 59, and the inner end of the boom with said member 59 is passed back over the platform under one of the braces such as 44, alongside the mast 10, and perhaps alongside the motor and windlass, so that the whole boom and its ropes and chains are loaded onto the platform car, and the latter can go back to the shops on its own power if desired. Obviously the coupling member 58 can be employed at this time for hitching the car to another car or perhaps several which it is desired to transport to the shops. The machine will doubtless be kept in the yard in this condition, especially if it is employed for wrecking purposes,

and when occasion for its use again arises it will go to the scene of work and the boom reset as seen in Fig. 1, so that the derrick is again ready for service. The fact that the sheave 53 is above the horizontal pivot 61 permits the power driven windlass to be used for raising the boom after it has been coupled to the platform car at its inner end, and its outer end raised manually perhaps as high as the operators can lift it. While it is held in oblique position by the cable 41, the supporting cable 51 will be roved through the eyelet 50, drawn taut, and clamped at 78; and also the sluing cables or chains will be roved through the eye-bolts 74 and 75, drawn taut with the boom in the position desired, and connected up by means of their hooks. Now these chains hold the boom against lateral movement, but also they serve in a measure to hold it supported because the eye-bolts are above the pivot 61, but the supporting cable 51 will take most of the weight of the boom and load, and through the guys 45 and 46 this weight is conveyed to the other and heavier end of the platform car. The hoisting cable may then be loosened, and the tongs will descend ready for service. This possibility of using machine power to quickly raise the heavy boom, is due to the fact that the sheave 53 is above the pivot 61, while the points of attachment 50 and 74 are respectively above said sheave and pivot.

Having thus described my invention, what I claim and desire to secure by Letters Patent is:

The herein described railway derrick comprising a platform car having a mast rising rigidly from one end, braces for said mast, a coupling member on the end of the car adjacent said mast, the latter having an opening above the platform of the car, a sheave therein for the hoisting cable; a boom, a block mounted on a horizontal pivot at its inner end and constituting a second coupling member, a coupling pin detachably and pivotally connecting said block with the coupling member on the car at a point beneath the platform thereof, eye-bolts in said platform, slue chains leading from the boom and adjustably connected with said eye-bolts, a supporting cable leading from the upper end of the boom and adjustably connected with the upper end of the mast, and a sheave in the outer end of the boom for said hoisting cable.

In testimony whereof, I affix my signature in the presence of two witnesses.

RICHARD J. VAUGHAN.
